VALVE MECHANISM FOR INTERNAL
COMBUSTION ENGINES

Thomas Noah Smith, San Antonio, Tex.

Application February 3, 1933, Serial No. 655,110

6 Claims. (Cl. 123—79)

This invention relates to internal combustion engines. More particularly it relates to that type of internal combustion engine shown in Patent No. 1,304,753, Blumberg in which the cylinder head is formed with a chamber therein into which the intake and exhaust valves open and having a main valve controlling communication between the chamber and the cylinder proper.

It is an object of this invention to provide a motor of this general type in which the intake and exhaust valves may be removed through the main valve port.

Another object of the invention is to provide a cylinder head for an engine of this type which may be cast in one piece and still permit the installation and removal of the intake and exhaust valves.

Still another object of the invention is to provide a cylinder head in which the intake and exhaust valves have their axes inclined to the axis of the cylinder to facilitate their removal.

Still another object of the invention is to provide an engine in which the valves are carried by the cylinder head and each operated by a separate cam shaft.

Still other and further objects of the invention will hereinafter appear.

In the drawings:

Figure 1 is a front end view of a motor constructed in accordance with the invention;

Figure 2 is a sectional view taken on the line 2—2 of Figure 1;

Figure 3 is a sectional view taken on the line 3—3 of Figure 2 with one of the valve assemblies removed showing the manner in which a valve may be withdrawn; and

Figure 4 is an inverted plan view of the cylinder head with the valves and guides removed.

With more particular reference to the drawings, 1 represents one cylinder of a multiple cylinder engine. This cylinder may be provided with fins 2 in order that it may be air cooled, as shown in the drawings or may be provided with a suitable water jacket, as is well known in the art. The cylinder 1 is provided with a cylinder head 3 which also may be air cooled by means of fins 4. This cylinder head is preferably cast in one piece as is shown and is formed with a chamber 5 therein. This chamber 5 has communication with the cylinder proper through a pair of main ports 6 in the wall between the chamber and the cylinder.

Opening into the chamber from the sides are a pair of intake ports 7 and a pair of exhaust ports 8. The roof or upper wall of the chamber 5 is peaked preferably being formed of two sub-

stantially plane surfaces meeting at an obtuse angle. The intake ports opening into the chamber through one of the plane surfaces and the exhaust ports through the other. At the inner ends of the intake and exhaust ports are formed valve seats 9 and 10, respectively, which, it will be seen, lie in planes which are substantially inclined from the horizontal.

A pair of main valves 11 are mounted for reciprocating movement substantially parallel with the axis of the cylinder in the cylinder head and serve to control communication through the main ports 6 between the chamber 5 and the cylinder. The main valves 11 are preferably mounted in removable valve guides 12 which tightly fit into suitable openings in the cylinder head. Similar valves, such as 13, are provided for controlling flow through the intake and exhaust ports 7 and 8.

A pair of intake and a pair of exhaust valves 20 are preferably mounted for reciprocating movement in suitable valve guides such as 14. These valve guides comprise a lower cylindrical portion 15 adapted to fit tightly into a suitable opening in the cylinder head and are provided with a shoulder 15^a adapted to seat against the upper surface of the cylinder head and an upwardly extending cylindrical portion 16 adapted to form a guide for the valve stem a substantial distance above the surface of the cylinder head. It is, of course, inherent in poppet valves that the axis of the valve be disposed perpendicular to the plane in which the valve seat lies. As set forth above, the intake and exhaust valve seats 9 and 10 lie in planes which are substantially inclined from the horizontal due to the sloping roof of the chamber 5. It will, therefore, be apparent that the valve stems 13 are inclined a corresponding amount from the axis of the cylinder. Preferably the valves are inclined sufficiently so that their axes lie on lines which extend through the main ports 6. Thus it is possible to machine the valve seats by means of rotatable tools inserted through the port 6 axially of the valve seat.

The lower cylindrical portions of each of the 45 valve guides are made relatively thick and are adapted to be withdrawn from the cylinder head when it is desired to remove the intake and exhaust valves. It will be noted that the overall diameter of the intake and exhaust valves is 50 slightly less than the diameter of the ports 6 connecting the cylinder and the chamber. Due to the thickness of the lower cylindrical portion 15 of the valve guide it will be seen that when the valve guide is withdrawn the stem of the valve 55

may be tilted in the opening in the cylinder head sufficiently to clear the edge of the port 6 and permit its removal through this port. This broad principle of removable valve guides which permit 5 the tilting and removal of valves is disclosed in detail in applicant's prior Patent No. 1,255,806. The manner in which the intake and exhaust valves may be removed is illustrated by the positions of the valve 13 as shown in dotted lines at 10 the right hand side of Figure 3.

In the embodiment shown in the drawings as above described it will be noted that in each cylinder two main valves are shown and also two intake valves and two exhaust valves. It will 15 be apparent, however, that in general the same advantages and beneficial results will be obtained if a single main valve and a single intake and exhaust valve is provided for each cylinder. The advantages of the dual valve motor are well known but it has been found particularly advantageous in a motor of this type. The two valves permit a considerable increase in the opening and hence freer and more complete intake and 20 discharge of gases.

25 The cam means for operating the valve comprises a shaft 17 which is preferably connected by suitable gearing to the crank shaft of the motor and extends parallel with the front end of the motor. This shaft 17 is preferably enclosed 30 in a casing 18. The shaft is provided at its upper end with a bevel gear 19 and which meshes with another suitable bevel gear 20 which is secured to the front end of a central cam shaft 21. Rotatably mounted on either side of the main cam 35 shaft 21 are intake and exhaust cam shafts 22 which are directly geared through the gears 23 and 24 to the main cam shaft. It will thus be seen that the revolution of the cam operating shaft 17 will cause all three over-head cam shafts 40 to rotate synchronously. Each of the valves 11 and 13 is provided with a washer 25 secured to the upper end of the valve stem. Confined between this washer 25 and the shoulder 15 of the valve guide is a compression valve spring 26 adapted to 45 hold the valve against its seat. An inverted cup or piston 27 is placed over the upper end of the valve stem and washer to provide a surface on which the cam may operate. Each pair of valves is enclosed by a casing such as 28 which surrounds 50 the portion of the valve stem which extends above the cylinder head and serves as an additional guide for the valves.

The cam shafts 21 and 22 are provided with 55 suitable cams 30 which operate on the upper surfaces of the inverted cups 27 and cause reciprocation of the valves. These cams are so arranged that they will cause the main valves 11 to open simultaneously with the exhaust valves and remain open while the burnt gases from the cylinder 60 are discharged into the chamber 5 and out through the exhaust port. The exhaust valves will then close and the main valves 11 will continue to remain open while the intake valve opens and a fresh charge is drawn into the cylinder. 65 The intake valves and the main valves are then closed simultaneously.

70 It will, therefore, be seen that the exhaust valves are not constantly exposed to the heat of the explosion and the passage of the hot gases from the cylinders. The main valves 11 although exposed to each explosion within the cylinder will be in some measure cooled by the passage of the incoming cool gases of the intake charge and will therefore be alternately heated and cooled. It is 75 an object of this invention to provide a motor in

which the valves may be kept as cool as possible and thus add materially to their life.

Engines having valve arrangements somewhat similar to the above have long been known in the prior art as evidenced by the patent to Blumberg above referred to. However, the defects and difficulties of the inventions shown in the prior art are numerous. In the present invention it is seen that it is possible to cast a cylinder head for this type of motor in a single one piece casting and yet permit the machining of the valve seats within the chamber in the cylinder head and also permit the easy removal of the intake and exhaust valves. It will be seen that the intake and exhaust valves may be removed by withdrawing the 10 valve guides 14 and tilting the valve stems sufficiently to permit the valves to pass through the main ports 6. This is possible due to the fact that the intake and exhaust valves are inclined at an angle to the axis of the cylinder and to the axis 15 of the main valve. Inasmuch as to permit this, it is necessary to provide inclined intake and exhaust valves, it has been necessary also to provide independent cam shafts for each set of valves in order to effect efficient operation of the motor. 20 In engines of this general type it is customary to provide lateral intake and exhaust ports and hence the inclination of the intake and exhaust valves permits a substantial straightening out in the passage ways from the cylinder through the 25 ports. Also, the inclination of the valves and their seating on the inclined roof of the chamber in the cylinder head permits a maximum effective opening of the valves in a minimum amount of space 30 due to the fact that relatively larger valves may be employed. Many and various modifications 35 of the invention are obvious from the foregoing only one of which has been illustrated in the drawings.

What I claim is:

1. In an internal combustion engine, a cylinder, a cylinder head, a chamber in said cylinder head, a main port connecting said chamber and said cylinder, a main valve for controlling communication between said chamber and said cylinder, 45 intake and exhaust ports communicating with said chamber, reciprocating intake and exhaust valves controlling said intake and exhaust ports and means permitting the removal of said valves through said main ports.

2. In an internal combustion engine, a cylinder, a cylinder head, a chamber in said cylinder head, a main port connecting said chamber and said cylinder, a main valve for controlling communication between said chamber and said cylinder, 55 intake and exhaust ports communicating with said chamber, reciprocating intake and exhaust valves controlling said ports, removable valve guides fitted in said cylinder head and when removed permitting tilting of the valves where- 60 by they may be removed through said main port.

3. In an internal combustion engine, a cylinder, a cylinder head, a chamber in said cylinder head, a main port connecting said chamber and said cylinder, a main valve controlling communication 65 between said chamber and said cylinder, intake and exhaust ports communicating with said chamber, intake and exhaust valves, having axes inclined to the axis of the cylinder for controlling said intake and exhaust ports, and means for 70 mounting said intake and exhaust valves in said head whereby removal of said valves through said main port may be made.

4. In an internal combustion engine, a cylinder, a cylinder head, a chamber in said cylinder head, 75

a main port connecting said chamber and said cylinder, a main valve controlling communication between said chamber and said cylinder, intake and exhaust ports communicating with said chamber, intake and exhaust valves, having axes inclined to the axis of the cylinder for controlling said intake and exhaust ports and relatively long removable guides for the stems of said valves, whereby when a guide is removed the valve may be tilted laterally to permit its removal through said main port.

5. In an internal combustion engine, a cylinder, a one piece cylinder head having a chamber therein, a port connecting said chamber and said cylinder, a main valve for controlling said port intake and exhaust ports communicating with said chamber and intake and exhaust valves for

controlling said ports, said intake and exhaust valves having their axes inclined to the axis of the cylinder and means permitting the removal of said valves through said main port.

6. An internal combustion engine having a cylinder, a cylinder head, a chamber within said cylinder head, a main port connecting said chamber and cylinder, a main valve for controlling said main port, intake and exhaust ports communicating with said chamber, intake and exhaust valves for controlling said intake and exhaust ports, the axes of said intake and exhaust valves being inclined to the axis of the cylinder and extending through said main port whereby they may be removed therethrough. 10

THOMAS NOAH SMITH.
